United States Patent Office

Des. 208,940
Patented Oct. 17, 1967

208,940

FLASHLIGHT OR SIMILAR ARTICLE

Walter E. Moore, Trumbull, Conn., assignor to General
Electric Company, a corporation of New York

Filed July 1, 1966, Ser. No. 2,908

Term of patent 14 years

(Cl. D48—24)

Fig. 3.

Fig. 2.

Fig. 1.

Fig. 4.

Fig. 5.

Fig. 6.

FIG. 1 is a bottom plan view of a flashlight embodying my new design;

FIG. 2 is a side elevational view thereof;

FIG. 3 is a top plan view thereof;

FIG. 4 is a perspective view of the flashlight embodying this design;

FIG. 5 is an elevational view of the flashlight showing the end from which light is emitted; and

FIG. 6 is an elevational view showing the end of the flashlight opposite that illustrated by FIG. 5.

I claim:

The ornamental design for a flashlight or similar article, substantially as shown.
